UNITED STATES PATENT OFFICE.

JOHN F. SEIBERLING, OF AKRON, OHIO.

TYPE-WRITING MACHINE.

SPECIFICATION forming part of Letters Patent No. 470,214, dated March 8, 1892.

Application filed July 2, 1888. Serial No. 278,766. (No model.)

To all whom it may concern:

Be it known that I, JOHN F. SEIBERLING, of Akron, county of Summit, and State of Ohio, have invented a new and useful Improvement 5 in Type-Writing Machines, of which the following is a full, clear, and exact description, reference being had to the accompanying drawings, making part of this specification.

My invention relates to an improvement in 10 type-writers or machines in which movable types are acted upon or actuated by a system of levers for producing impressions upon a sheet of paper or other material.

My invention relates more particularly to 15 the construction and arrangement of the machine-frame and type-levers; to the means for covering the inking ribbon or pad when not in use and thereby protecting the same from injury resulting from the action of the air 20 thereon, evaporation of the ink, accumulation of dust and dirt, or other causes; also, to the means for locking the type-levers or their actuating mechanism while the ink ribbon or pad is covered, and in certain other features 25 of construction and arrangement hereinafter set forth.

In the accompanying drawings, Figure 1 represents a section from front to rear of a type-writing machine embodying my improvements. Fig. 1^a is an enlarged sectional view showing the manner of adjusting the inking device. Fig. 2 is a side elevation of the ink-pad holder. Fig. 3 is a plan view of the parts shown in Fig. 1. Fig. 4 is a sectional view 35 similar to Fig. 1, showing a modified form of type-actuating mechanism and means for covering the ink-pad; and Fig. 5 is a plan view of the same.

A represents the base of a type-writing machine, upon which all the other parts are mounted.

B B indicate the uprights or standards, upon which a ring or annular frame C is secured by screws or in any usual manner.

D represents an annular piece or ring which forms the ink-pad holder. Said ring surrounds, snugly, the annular frame C, and is adjustably connected therewith by means of screws c, passing through inclined slots d, 45 Fig. 2. The pad-holder is of annular form in cross-section, or, more accurately speaking, has two vertical portions D and D² connected

by a horizontal portion of flange D', as best illustrated in Fig. 1^a, thus forming a receptacle for an inking-pad E. The latter is annular in form, is composed of any material adapted to the purpose of receiving and holding ink, and when in position for use occupies a place just above the plane of the annular frame C, for a purpose that will appear. When 55 the type-writer is not in use, the pad-holder is lowered by rotating the same partially around the frame C, when the inclined grooves act upon the pins or screws c, the effect being to depress the pad-holder and cause the inking- 60 pad to take up a position in horizontal line with said frame C, as shown in dotted lines, Figs. 1 and 1^a, against which it rests in close contact or proximity, the object being apparent—viz., to protect said inking-pad from injury of 70 any kind, whether from dust, dirt, evaporation of the ink, or other cause. Another object in adjusting the ink-pad is to bring a new surface thereof into position for the types to get their supply of ink from and also to prevent 75 too much wear in one spot, caused by said types striking and resting continually in one place on the ink-pad. Knobs d' may be employed for enabling the operator to adjust the pad-holder.

For the purpose of securing the inking-pad in place, and for the additional purpose of protecting the types and type-levers from injury when the machine is not in use, a ring or cap-piece F is slipped over the pad-holder D, as 85 shown, being secured by fitting tightly or snugly around the portion D² of the pad-holder D, or it may be secured in any usual or preferred manner. The cap-piece F is also angular in cross-section, its horizontal portion 90 overlying the inking-pad and its upper vertical portion being in the same vertical plane with the inner face of the inking-pad. When the pad-holder is lowered, as described above, the inner portion of the cap F will occupy the 95 position lately occupied by the inking-pad, as shown in dotted lines in Fig. 1^a. As the inking-pad when in use is located in such position that the types will rest against it, accordingly when the pad-holder is lowered the upper portion of the cap F will occupy a similar 100 relation to the types and prevent injury to the same.

G represents a central standard or post, and

G' an upright or support adjustable vertically in a socket in said standard, being secured at the desired adjustment by a screw g'. Said support G' is provided at its upper end with 5 a hub and radiating arms g², which uphold a ring H, preferably rectangular in cross-section, as shown in Fig. 1. Upon this ring a number of guide-plates I are secured by means of foot flanges and screws, as shown, or in other 10 suitable manner. Said guide-plates I are each provided with a guide-slot I' and vertical guide wall or projection i, for a purpose that will hereinafter appear.

J J indicate the type-levers or levers which 15 carry the types used in making the impressions. At their upper or type ends these levers are by preference made solid; but at or near their center they are bifurcated or formed each with two similar parallel arms, which 20 embrace the ends of links or arms K. The latter extend from said connection outward to beyond the annular frame C, where they are pivoted to lugs of an annular frame L, surrounding the standards B and attached thereto 25 by means of brackets M, as shown. The type-levers are also provided each with a pin or roller j', which is adapted to travel in the slot I' of the guide-plate I and against the vertical projection i of said guide-plate, for 30 assisting in the proper guidance of the type-lever in its movements. By this arrangement it will be seen that the type-levers have no fixed pivots, but that such pivots change or move in guide-slots and constitute what I term "floating" type-levers. Supplemental arms K' are also employed, pivoted at their outer ends to lugs of frame L and extending inwardly in a plane substantially parallel with arms K, referred to. 35 The inner ends of these levers form stops, against which projections j² of the type-levers J strike and rest, when operated as hereinafter described, for limiting the movement of the type-lever and directing its course in a 40 vertical line, so that the type may strike squarely against the paper and produce a clean sharp impression. The arms K and K' are connected by links k. Pendent links or rods N connect the arms K' with a series 45 of key-levers O of different lengths, each suitable as to length to the location of the link or rod with which it is connected, and said key-levers are pivoted at suitable points in the fulcrum-posts P on the base A of the 50 machine. The levers O all extend toward the front of the machine, as shown in Figs. 1 and 4, (left hand), where they are provided with upwardly-extending rods R, to which the operating-keys S of the type-writer are 55 secured.

T indicates an inclined table, which is provided with perforations, through which the rods R pass and are steadied in their movements, the table being secured by its connection with the outer ring L at its upper end and with a vertical plate or support T' at its lower end.

U represents the platen or roller which carries the paper to receive the impressions of the types. 70

In Fig. 1 the type-levers are shown in both the operative and inoperative positions, with the operating devices and links in corresponding positions. When a key is depressed, the rod R depresses the end of the lever O, to 75 which it is connected. The opposite end of said lever is thus elevated and operates through the medium of link or rod N to rock the arm K upward on its pivot. The inner end of arm K is thus caused to act upon and 80 throw up the type-lever J until the type j thereon strikes the paper and produces an impression. The key being released, a suitable spring O' elevates the outer end of lever O, thus returning the type-lever and its 85 connections to their position of rest, the types j lying against or in contact with the inking-pad E, as shown.

A modified form of guide-plate I is shown in Fig. 4, in which said plate is provided with 90 an L-shaped slot I'. Said slot is inclosed, as shown, which enables me to dispense with the supplemental arm K', as the pin j', not being able to escape from the slot I', the latter acts in place of arm K' to limit the movement of 95 the type-lever and guide the same in a vertical path. Now when the type-writer is not in use the ink-pad holder is adjusted to its lower position, as above described, or until the ink-pad E occupies the position shown in 100 dotted lines in Fig. 1^a. The cap F is thus brought down and protects the types from injury. By the adjustment of the pad-holder to such position the lower edge or face d² thereof will descend to the position indicated 105 in dotted lines in Figs. 1 and 1^a, which will prevent the arms K from rising, thus locking the type-actuating mechanism in the position of rest. It will thus be seen that by the adjustment of the ink-pad holder the ink-pad 110 and type are covered and protected and the type-actuating mechanism locked or held inoperative until the pad-holder is moved back to its former position.

In Figs. 4 and 5 a modified form of devices 115 for covering the inking-pad is illustrated. The movable pad-holder in this case is dispensed with and the annular frame C is recessed or cut out to receive the annular inking-pad E. The inking-pad being thus stationary, the upper vertical portion of the cap F is also dispensed with. The outer ring L may also be dispensed with and the arms K pivoted directly to the annular frame C, as 120 shown in Fig. 4.

The device for covering the inking-pad is composed of an annular plate or cylinder V, extending around within the annular frame C and fitting snugly against the inking-pad E, as shown. Said covering-plate V is provided 125 with slots v, through which are inserted pins or screws v', thus allowing said plate to be adjusted up and down for covering or uncovering the inking-pad. To provide mechanism 130

for adjusting said plate V, links w are employed, attached at one end to said plate and operated at the other end by crank-arms w' on rock-shafts W.

5 X indicates a bar or plate, which extends transversely across and near the front of the machine and underlies the key-levers O, as shown in Fig. 4. Said bar connects the crank-shafts W through the cranks x x, so that when one shaft W is operated by a handle or crank Y for that purpose the other shaft W will also be caused to operate for simultaneously operating the links w and adjusting the plate V. The cranks w' and x are so arranged that 15 when the plate V is elevated to cover the ink-pad the bar or plate X will also be raised to a position directly beneath the key-levers O, thus locking the type-actuating mechanism in the position of rest simultaneously with 20 the covering of the ink-pad, both of which results are accomplished by only one act on the part of the operator—viz., operating crank Y.

Having thus described my invention, what I claim as new, and desire to secure by Letters 25 Patent, is—

1. In a type-writing machine, the combination, with the annular inking device located in the path of the types, of an annular cover for protecting the inking-face thereof, for the 30 purpose and substantially as described.

2. In a type-writing machine, the combination, with the annular inking device, of an annular covering device therefor, and means, substantially as described, whereby said inking device may be covered or uncovered, for 35 the purpose substantially as described.

3. In a type-writing machine, the combination, with the main frame, of a movable annular inking device, and means, substantially 40 as described, for operating the same to move it as a whole behind a covering-surface and beyond the path of the type, substantially as set forth.

4. In a type-writing machine, the combination, with the frame thereof, of an inking device, a holder for carrying the same provided with the inclined slots, the laterally-projecting guide-pins attached to the frame of the machine and entering said inclined slots, 50 whereby the pad-holder may be adjusted in height and covered in the manner substantially as and for the purpose described.

5. In a type-writing machine, the combination, with the annular frame thereof, having 55 the laterally-projecting pins c, of the annular ink-pad holder provided with the inclined slots, and suitable knobs for operating said holder to move it behind a covering-surface,

for the purpose and substantially as described.

60

6. In a type-writing machine, the combination, with the type-actuating mechanism, of an ink-pad holder and means for adjusting said holder for locking the type-actuating mechanism in inoperative position, substantially as described.

7. In a type-writing machine, a combined ink-pad holder and type-actuating-mechanism-locking device, in combination with means operating in connection therewith to simultaneously cover the inking device and lock the type-actuating mechanism, substantially as specified.

70

8. In a type-writing machine, the combination, with the annular frame and the type-actuating mechanism, of the annular ink-pad holder provided with the downwardly-projecting flange, and means, substantially as described, for adjusting said annular ink-pad holder for locking the type-actuating mechanism in inoperative position.

75

9. In a type-writing machine, the combination, with the type-levers and key-levers, of the interposed links N, arms K, and guide-plates I, a stationary support for the latter, 85 and the pivoted stop-arms K' parallel to the arms K, all arranged and operating substantially as described.

10. In a type-writing machine, the combination, with the annular ink-pad and stationary central ring H, of the guide-plates I, type-levers, key-levers, and interposed pivoted arms K, links N, pivoted stop-arms K', parallel to the arms K, and the springs O', all substantially as and for the purpose described.

95

11. In a type-writing machine, a series of floating type bars or levers, each provided with a guide pin or roller, and guide-plates for directing the movement of said type bars or levers, in combination with the arms K and K', links N, and the key-levers for actuating the same, as and for the purpose specified.

100

12. In a type-writing machine, the combination of a series of type levers or bars, each provided with a guiding pin or roller, the slotted guide-plate in which said pin travels, and the key-levers, links N, and arms K and K', all arranged and operating substantially as described.

105

In testimony whereof I have hereunto set my hand this 27th day of June, A. D. 1888.

JNO. F. SEIBERLING.
